UNITED STATES PATENT OFFICE.

PAUL DE HUFF AND WALTER A. WOOD, OF LOS ANGELES, CALIFORNIA.

COLLAPSIBLE CORE.

Application filed November 30, 1923. Serial No. 677,785.

This invention relates to collapsible cores for concrete construction purposes.

It is an object of the invention to provide a core which is collapsible both laterally and longitudinally and which may therefore be readily withdrawn after a concrete wall or body has sufficiently set about the core.

A further object is to provide a core of simple and inexpensive form of construction and comprising substantially duplicate and therefore interchangeable and reversible parts.

Another object is to provide a collapsible core of but a few simple elements.

Other objects and advantages will be made manifest in the following specification of an embodiment of the invention illustrated in the accompanying drawings, wherein:

Fig. 1 is a perspective showing the use of the improved core.

Fig. 2 is a plan of a core.

Fig. 3 is a perspective showing the core spacers in place.

Fig. 4 shows an extension plate in a core.

The present invention consists of a metallic hollow core structure for use in the construction of concrete bodies such as walls of buildings.

The core consists of side panels 2, having flat wall portions with inturned top and bottom flanges 3. The panel parts 2 have curved ends 2^a which are overlapped and fastened as by bolts 4. Thus a pair of parallel panels 2, when secured at their over-lapping ends, form a U-shaped core section. Two of these U-shaped sections are adapted to be assembled with their flat ends 2^b in over-lapping relation as clearly shown in Fig. 2 and thus form a hollow core structure adapted to be readily disposed in a mold box indicated at M into which plastic concrete C is poured for the construction of a wall or other concrete body.

The hollow cores may be of any dimensions and are adapted to be placed at suitable locations in upright positions as in Fig. 1.

To prevent the collapse of the hollow cores, keepers or spacers are provided and these consist of substantial plates 5 substantially of channel form and having outwardly turned flanges 5^a to be disposed upon the flanges 3 of the core. The flanges 5^a are provided with apertures 5^b to receive staple-

like devices 6, the legs of which are adapted to be extended into apertures 3^a of the flanges 3, and therefore operate to key the side panels of the core to the keepers 5. The keepers are adapted to be pulled from their positions after the concrete mass C has set and for this purpose the keepers may be connected as by sufficiently strong pieces of rope R which may be grasped at the upper end and pulled to dislodge the keepers and the retaining staples 6 from the cores. Upon removal of the keepers the core sections may then be longitudinally and laterally collapsed to be drawn from the chambers in the concrete body.

For positioning the top keeper of each core a transverse strap 10 is nailed or otherwise secured to the mold boards of the mold M, and these straps are bolted at 11 to the flanges of the upper keeper 5, as shown in Fig. 1.

When desired an expansion plate 15 can be introduced at the overlapping portions 2^a on the ends of the core and the core can be lengthened by the introduction of an expansion plate 15 under the overlapping ends 2^b of the plate. These plates are perforated to receive the fastening bolts 4.

Different lengths of spacers 5 may be employed according to the width of the extension plates 15.

Further embodiments, modifications and variations may be resorted to within the spirit of the invention.

What is claimed is:

1. A collapsible hollow sheet metal core for concrete construction purposes, said core consisting of substantially U-shaped end sections adapted to be assembled with their free ends in overlapping relation to form a core, the top and bottom edges of the core sections being provided with in-turned flanges, and spacing means connectable to the flanges to keep the core walls in rigid position during pouring of the concrete mass into a mold, said means including devices adapted to be disposed from the top and bottom flanges of the core, and means for facilitating the removal of the lower spacing device from the core to permit the latter to be collapsed.

2. In combination, a sheet metal collapsible concrete mold core, spacing devices applicable to the upper and lower portions of the core to sustain the same, and staple-like

fastening means for connecting the spacing devices to the core, and permitting ready removal of the devices from the core.

3. In combination, a sheet metal collapsible concrete mold core, spacing devices applicable to the upper and lower portions of the core to sustain the same, and staple-like fastening means for connecting the spacing devices to the core, and permitting ready removal of the devices from the core, said means consisting of staple-like parts.

4. A collapsible metal core for concrete construction including U-shaped sections, and spacing members having outwardly turned flanges adapted to rest upon the parallel walls of said sections with portions disposed therebetween so as to prevent collapse of said sections.

5. A collapsible metal core for concrete construction comprising two U-shaped sections, said sections including panels having inturned flanges at their tops and bottoms, a spacing member adapted to engage the upper flanges of said panels to keep them in proper, spaced relation, a second spacing member engageable upon the lower flanges of said panels to keep them in proper, spaced relation, and a tie means connecting said spacing members to facilitate removal of said second spacing member.

6. A panel section adapted to form a part of a collapsible core for concrete construction comprising a panel having an end bent out of the plane of the body of the panel, and flanges bent out of the plane of the body at the top and bottom thereof, there being apertures formed in the flanges and along the side edge of the mentioned bent end as and for the purpose described.

40 7. A panel section adapted to form a part of a collapsible core for concrete construction comprising a panel having an end bent out of the plane of the body of the panel, and flanges bent out of the plane of the body at the top and bottom thereof, there being apertures formed in the flanges and along the side edges of the panel as and for the purposes described.

8. A collapsible core for concrete construction comprising two U-shaped sections, each section including panels having bent ends, a spacing plate adapted to be inserted between the bent ends, and means for connecting the bent ends of the sections together or to the edges of the spacing plate.

9. A collapsible core comprising two U-shaped sections, said sections including panel sections having inturned flanges at their tops and bottoms, and spacing means adapted to rest upon the top surfaces of the flanges, said spacing means having portions disposed between the edges of the flanges.

10. A collapsible core comprising two U-shaped sections, said sections including panel sections having inturned flanges at their tops and bottoms, spacing means adapted to rest upon the top surfaces of the flanges, said spacing means having portions disposed between the edges of the flanges, and means connecting the spacing means resting upon the top flanges to the spacing means resting upon the bottom flanges.

11. A collapsible core comprising two U-shaped sections, said sections including panel sections having inturned flanges at their tops and bottoms, spacing means adapted to rest upon the top surfaces of the flanges, said spacing means having portions disposed between the edges of the flanges, and fastening devices extending through the spacing means and through said flanges.

12. A collapsible core comprising two U-shaped sections having inturned top and bottom flanges, and removable spacing means engageable upon the flanges of each section to keep the sides of the sections properly spaced.

13. A collapsible core comprising two U-shaped sections having inturned top and bottom flanges, and removable spacing means engageable upon the flanges of each section to keep the sides of the sections properly spaced, said spacing means serving also to connect the flanges of one U-shaped section to the flanges of the other U-shaped section.

14. A collapsible core comprising a plurality of substantially U-shaped sections, flanges extending inwardly from the top and bottom of each side of each section, said flanges having apertures therein, and elements removably positioned in said apertures.

In testimony whereof we have signed our names to this specification.

PAUL DE HUFF.
WALTER A. WOOD.
